SIX-WAY STOPCOCK

Robert L. Fuson, North Branch, N.J., and Wesley S. Larson, Enfield, Conn., assignors to Ethicon, Inc., Somerville, N.J.

Filed Sept. 26, 1974, Ser. No. 509,361

Term of patent 14 years

Int. Cl. D23—01

U.S. Cl. D23—38

FIG. 1.

FIG. 2.

FIG. 4.

FIG. 6.

FIG. 7.

FIG. 2.

FIG. 5.

FIG. 1 is a perspective view taken from the top of a six-way stopcock embodying our new design;

FIG. 2 is a bottom perspective view thereof;

FIG. 3 is a top plan view thereof;

FIG. 4 is a bottom plan view thereof;

FIG. 5 is an elevational view taken from one side thereof, the opposite side being a mirror image of the side shown;

FIG. 6 is a left end elevational view thereof; and

FIG. 7 is a right end elevational view thereof.

We claim:

The ornamental design for a six-way stopcock, substantially as shown and described.
